UNITED STATES PATENT OFFICE.

LINUS WOLF, OF ZURICH, SWITZERLAND, ASSIGNOR TO JOHN RAHN AND FRED HESSLER, BOTH OF CHICAGO HEIGHTS, ILLINOIS.

IGNITING DEVICE.

1,181,817.

Specification of Letters Patent.

Patented May 2, 1916.

Application filed August 5, 1912. Serial No. 713,221.

To all whom it may concern:

Be it known that I, LINUS WOLF, subject of the German Emperor, residing at Zurich, Switzerland, have invented a certain new and useful Improvement in Igniting Devices for Gas-Lamps, of which the following is a specification.

This invention relates to improvements in igniting devices for gas lamps, and has for its object to provide a new and improved device of this description.

The invention is illustrated in the accompanying drawings, wherein—

Figure 1 is a front view of a gas burner 15 with the igniting device attached thereto; Fig. 2 is a side view of the device shown in Fig. 1; Fig. 3 is an enlarged sectional view taken on line 3—3 of Fig. 1; Fig. 4 is a sectional view taken on line 4—4 of Fig. 3; Fig. 5 is a sectional view taken on line 5—5 of Fig. 3; Fig. 6 is a view of the support for the spark producing device as stamped out and prior to being bent into shape.

Like numerals refer to like parts throughout the several figures.

In the drawings, I have illustrated a gas burner 1 particularly adapted for lamps used in connection with automobiles. An igniting device 2 is connected with the burner. This igniting device comprises a support which is preferably made from a single piece of metal. As herein shown, this support consists of a body portion 3 having projections 4 and 5 which are provided with openings 6 for the pin 7 carrying the rotatable part of the device. Connected with the projection 5 is a piece 8 adapted to be bent so as to form a receptacle or receiving device for the spark producing material. A stop piece 9 also projects from the body portion and acts as a stop for the rotating part. An engaging piece 10 projects from the body portion and is adapted to be bent around so as to engage the burner 1. This engaging piece is cut away at 11 and there is a hook projection 12 connected with the body portion to which is connected the end of the spring 13 which presses the spark producing material against the rotating part. The engaging part 10 is provided with an opening 14 and a body portion with an opening 15 which are opposed to each other when the engaging part is bent around and through which a bolt, pin or other clamping and holding piece is passed and by means of

which the igniting device is held in place on the burner. The support is first stamped out as shown in Fig. 6 and the parts are then bent to the positions shown in Figs. 1, 2 and 3. The openings 6 in the projecting parts 4 and 5 are then opposed to each other. A cylindrical part 16 is then placed between the parts 4 and 5. This cylindrical part is supported upon the pin 7 and is hollow, there being located inside of it a coil spring 17 having one end 18 engaging the support so as to be held stationary. The other end is formed into a loop 19 which projects through a hole 20 in the cylindrical part and which acts as a handle for rotating the cylindrical part. By grasping the handle 19 the cylindrical part is rotated and the spring 17 energized. When the handle 19 is released, the spring presses the cylindrical part back until the spring strikes the stop 9. Upon the end of the cylindrical part is a roughened part 21. This roughened part is preferably made of steel or other hardened material and may be in the form of a file. The rotating part is reduced in diameter near its end and the roughened part formed into a circular form with the ends separated by a space, that is, the roughened part does not form a complete circle. A projecting part 22 on the cylindrical part extends into the space between the ends of the roughened part so as to prevent the roughened part from rotating on the cylindrical part. This projection may be formed in any desired manner as by upsetting or mutilating the rotating part so as to force the metal thereof outwardly at this point. The pin 7 passes through the rotating part and into the opening 6 and is held in place in any desired manner as by upsetting or battering the ends thereof. The piece 8 is bent around so that the ends are in proximity to each other as shown in Fig. 5 and is located above the piece of roughened material 21.

A piece 23 of spark producing material, such for example, as pyrophorus material, is loosely placed in the receptacle or receiving device formed by the piece 8 and a follower device 24 is inserted therein so as to engage the spark producing metal and is provided with a bent end 25 to which is connected the spring 13 which normally presses it against the spark producing metal so as to force said metal against the surface of the roughened piece 21. As illustrated in the

drawing, a bolt 26 is passed through the openings 14 and 15 and is provided with a nut 27 which may be tightened so as to clamp the igniting device to the burner. It will be noted that the spark producing device consists of the spark producing metal and the roughened piece 21 is arranged so that the spark is discharged directly toward the burner. In other words, there is a spark opening 28 arranged in the support 3 opposite the burner and this spark opening is arranged with relation to the engaging device 10 so that it will point directly toward the burner regardless of the position 15 of the igniting device. In other words, if the igniting device is rotated entirely around the burner, this spark opening will be pointed directly toward the burner at every point around the entire circle so as to 20 discharge sparks directly toward the burner in every position it occupies throughout its entire circle.

It will be noted that the present device is small so that it occupies very little space 25 and can be arranged at the side of the burner so as not to cause a shadow at the front. It will further be noted that the device is simple of construction and has few parts and can be made cheaply, and can be easily attached in position.

In operating the device, it is placed on the burner as shown for example in Fig. 1. The gas is then turned on and the handle 19 is moved away from the stop 9. This movement being performed by the hand will be comparatively slow. After being moved a part of a revolution, the handle is released and the energized spring rapidly moves the rotating part and the roughened part 21 back to their initial position. The roughened part moves along the lower surface of the spark producing metal 23 at a comparatively high speed and causes sparks to be discharged therefrom through the spark 45 opening 28 directly upon the gas emerging from the end of the burner. The gas is thereupon ignited.

This device in addition to being simple in construction is reliable and will last a long time. It permits the burner to be lighted without matches and it acts regardless of wind, rain or atmospheric conditions.

I claim:

1. An igniting device for gas lamps comprising a rotatable part, a support upon which it is mounted, a spring connected with said rotatable part and with a fixed part associated with said support, a portion of said spring bent outwardly so as to form a handle by means of which said movable part is moved and said spring energized, a spark

producing device associated with said movable part and located in the plane of the burner and an engaging device on said support for connecting it with the burner. 65

2. An igniting device for gas lamps comprising a spark producing device, a movable part for actuating the spark producing device, a support therefor made up of a single piece of material, a portion of said support bent so as to form an engaging device for the burner, a spring associated with said movable part, a portion of said spring projecting laterally therefrom so as to act as a handle for manipulating it and a stop 75 engaging said projecting portion of the spring so as to limit its movement.

3. An igniting device for gas lamps comprising a rough piece formed into a circular form with the ends separated by a space, a 80 cylindrical part projecting through said roughened part and having a portion thereof bent outwardly into the space between the ends of said roughened part, a piece of spark producing metal adapted to be engaged by 85 said roughened part and means for connecting said parts to the lamp burner.

4. An igniting device for gas lamps comprising a body portion, an engaging part integral therewith, adapted to be connected with the burner, a receiving device for the spark producing material formed integral with said body portion, two projecting parts on said body portion, a movable part mounted between said projecting parts 95 and adapted when moved to frictionally engage the spark producing material, an actuating spring connected with said movable part and an inclosing piece inclosing said spring and mounted between said projections. 100

5. An igniting device for lamps comprising a roughened piece, formed into a curved form, with the ends separated by a space, a cylindrical part projecting through said 105 roughened part, said cylindrical part provided with an engaging device between the ends of said curved roughened part, adapted to engage said ends and hold said roughened part against rotation with relation to said cylindrical part, a piece of spark producing material adapted to be engaged by said roughened part and a supporting device by means of which the parts are connected to the lamp burner. 110

Signed at Chicago, Illinois, this 22nd day of July, 1912.

LINUS WOLF.
